NEEDLE GUARD FOR SEWING MACHINES

Filed Jan. 9, 1925

2 Sheets-Sheet 2

UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

NEEDLE GUARD FOR SEWING MACHINES.

Application filed January 9, 1925. Serial No. 1,431.

This invention relates to guards or shields for sewing machines for preventing injury to the operator from flying pieces should the needle break while the machine is in operation. As it is desirable to permit ready access to the needle when the machine is stopped this invention provides means for moving the guard to and from its operative position between the needle and the operator so that when the machine is running it is in its operative position and when the machine is stopped it is automatically or at the will of the operator retracted. For more complete understanding of this invention reference may be had to the accompanying drawings in which:

Figure 1 is a side elevation of a button sewing machine showing the needle guard applied thereto.

Figure 2 is a detail bottom elevation of a portion of the machine head drawn to a smaller scale.

Figure 3 is a fragmentary detail.

Figure 4 is a front elevation of the same, certain parts being omitted.

Figure 5 is a detail section on line 5—5 of Figure 4.

Figure 6 is a view similar to Figure 4 but showing a modified construction.

Figure 7 is a fragmentary side elevation of the machine showing a modified form of guard actuating means.

Figure 8 is a fragmentary plan illustrating the same means.

Figure 9 is a fragmentary rear elevation of the same.

Referring first to Figure 1, a button sewing machine is shown having a work table 1, provided at one end with an upstanding portion 2 terminating in a horizontal arm 3, which carries on its forward end a head 4 for supporting certain of the sewing instrumentalities, such instrumentalities including a needle bar 5 to the lower end of which is fixed the needle 6. Positioned beneath the arm 3, is shown a button clamp of any suitable description as at 9 by which a button may be held in position so that the needle may pass through the holes thereof and sew the button to work positioned between the button clamp and the upper face of the table 1, as shown, in the usual manner.

At the forward lower edge of the head 4 is pivoted on a shaft 10 a needle guard 6', which as shown in Figures 4 and 6, com-

prises a rectangular frame 7 supporting a transparent window portion 8, which when the guard is rocked downwardly into the dotted line position shown in Figures 1 and 4, is in front of needle 6, and between the needle and the machine operator and closely adjacent to the needle. The transparent portion 8 permits the operator to watch the operation of the machine as the work is being sewed but should the needle break, the guard prevents flying portions thereof from escaping in the operator's direction. When the machine is stopped, however, it is desirable that the guard should be removed from in front of the needle, this being done in the present instance by rocking the guard on its shaft 10 upwardly as shown in full lines in Figures 1 and 4. In place of rocking the guard to and from its operative position about a horizontal axis as shown in Figures 1 and 4, it may, if desired, be rotated about a vertical axis as shown in Figure 6. As shown in this figure the shaft 10 is journaled in vertical position in bearings 11 projecting laterally from one side edge of the head 4. With this construction it may be rocked to take a position as shown in dotted lines in Figure 6 adjacent to the needle 6 and between the needle and the operator or it may be rocked into the full line position shown in Figure 6 where it is positioned at one side of the needle, the needle then being freely accessible to the operator.

In order to rock the guard whichever way it is pivotally mounted, the construction shown in detail in Figure 5 has been provided. It will be seen that the shaft 10 has fixed thereon a pinion 15 rotatable within a housing 16 projecting laterally from a tubular member or sleeve 17. This pinion meshes with the teeth of a rack 18 slidably through the sleeve 17, this rack being carried on the forward end of a thrust rod 20. As shown, the forward end of the thrust rod is threaded as at 21 and is screwed into the end of the rack bar 18, a check nut 22 being employed to fix the two in proper relative position. The forward end of the rack bar has fixed thereto a washer 25 of larger diameter than the rack bar, as by means of a screw 26, this washer forming a stop engageable with the forward end of the sleeve 17 to limit the rearward motion of the rack bar. It is evident that by pushing the thrust rod 20 forwardly from the position

shown in Figure 5, the pinion 15 will be turned in a direction to bring the guard to its operative position, while movement of the rack bar in the reverse direction as far as 5 permitted by the stop 25 will cause the guard to be moved out of its operative position. This guard is normally held out of its operative position by means of a coil spring 30 surrounding the thrust rod and bearing at its forward end on the rear end of the sleeve 17 as at 31 and at its rear end against a collar 32 fixed as by means of a set screw 33 to the thrust rod. This thrust rod is intended to be actuated by the mechanism for starting and stopping the machine. Such mechanism may be of any suitable type but as herein shown is of the construction fully shown, described and claimed in the application for patent of Harold W. Morris for stop mechanism, Serial No. 643,898, filed June 7, 1923, and it may be actuated therefrom in various ways, two of which are shown in the accompanying drawings.

25 Referring to the construction shown in Figure 1, it will be seen that the thrust rod 20 passes to the rear of the machine and through a perforation in a guide post 35 fixed to a bar 36 which forms part of a belt 30 shipper, the belt shipper fingers being indicated at 37 and 38. Forwardly of the post 35 the thrust rod 20 has affixed thereto, as by means of a set screw 40, a collar 41. In the position shown in Figure 1, the shipper 35 fingers 37 and 38 are positioned to hold the driving belt for the machine, (not shown) on a loose pulley 45 but by the motion forwardly of the belt shipper 36, the belt may be moved by these fingers on to a tight pulley 46 by which action the operation of the machine may be initiated. When this forward movement of the belt shipper is affected the post 35 is likewise moved forwardly, and this, impinging on the collar 41, causes the thrust rod 20 to be moved forwardly, thus causing the guard to be moved to its operative position as hereinbefore described. As soon as the belt shipper is moved rearwardly to bring the belt on to the loose pulley and to stop the machine, the post 35 is also moved rearwardly thus permitting the thrust rod 20 to move therewith under the action of the coil spring 30, which moves the thrust rod 20 rearwardly as far as is permitted by engagement of the collar 41 against the post 35. As shown in the Morris patent hereinbefore referred to, and in Figures 1 and 2, the belt shipper and stop member are caused to move forwardly by means such as a treadle which acts through a chain 50 to rock a bell crank lever 51 in a manner to cause its upwardly extending arm 52 to engage a pin 53 extending laterally from a plunger 54 which is connected in any suitable manner to the belt shipper.

When moved forwardly in this manner the plunger 54 may be latched in its forward position, for this purpose a latch 55 being shown, which engages behind a latch surface 56 on the plunger. As soon as this has 70 been affected and pressure removed from the treadle a spring 57 retracts the bell crank lever out of engagement with the pin 53 so that when the latch 55 is tripped by any suitable means the belt shipper is free to be 75 projected rearwardly to bring the shipper fingers into cooperative relation with the loose pulley by means of a spring 60 engaging a collar fixed to the plunger shaft 54. It may thus be seen that whenever the chain 80 50 is pulled downwardly to start the machine, the belt shipper is moved to bring the belt from the loose to the tight pulley and at the same time the needle guard is moved from its inoperative to its operative position, the action of the needle guard being the same whether the shaft 10 is journaled horizontally as shown in Figures 1 and 4, or vertically as shown in Figure 6, so far as 85 this action is concerned. Whenever the latch 55 is tripped to affect the stopping of the machine, the belt shipper moves the belt from the tight pulley to the loose pulley and stops the machine, and the spring 30 acts to move the guard into inoperative position 90 so that the needle is readily accessible.

In Figures 7, 8 and 9, a slightly modified connection to the stop mechanism is disclosed.

95 At 70 is shown a vertically extending rod 100 having a hook 71 at its upper end which may engage an arm on a rock shaft 80 which has fixed thereto an arm 81 connected by chain 82 to the button clamp 9, in order that this clamp may be raised from the work 105 table by a downward pull on the rod 70. This rod 70, is, however, so connected to the stop mechanism that it cannot be depressed while the machine is running. For this purpose the rod 70 is cut away at one 110 side as at 85 (Figure 3) so that when it is in one axial position only a rod 86, slidably mounted in the machine frame, may extend therewith. When the rod 86 is so extended the rod 70 is locked against vertical movement. The rod 86 is so connected to the belt shipper mechanism by a link 87 that it is so extended while the machine is running, thus holding the rod 70 elevated, and is retracted when the belt shipper is in machine stopped 115 position so that the rod 70 may be depressed to raise the button clamp from its button-presenting position. The lower end of this rod 70 is slidably guided through the frame 120 of the machine and has a chain 72 fixed thereto beneath the guiding portion. This rod 70 has fixed thereto near its upper end a collar 73 provided with a laterally extending pin 74. The thrust rod 20 passes through the post 35 upstanding from the belt shipper 125 36 130

in the same manner as herebefore described, but instead of the collar 41, a suitable collar shown at 75 is affixed to the push rod 20 forwardly of the post 35. This collar engages at its rear end on the downwardly extending arm 76 of a bell crank lever 77 pivoted at 78 to the machine frame. The other arm 79 of this bell crank lever is slotted as at 790 to take over the pin 74. 5 It will be seen therefore that when the chain 72 is lowered to raise the button clamp the bell crank lever 77 is rocked into the dotted line position shown in Figure 7 thus permitting the collar 75 to follow the lower 10 arm of this lever under the impulse exerted thereon by the spring 30, this action taking place only when the belt shipper is in loose pulley belt-engaging position. This construction so far as the rod 70 and the belt 15 shipper is concerned is fully disclosed in the application for patent of Harold Morris, Serial No. 643,897 filed June 7, 1923, for button sewing machine.

It will only be necessary to note herein 20 that whenever the machine is stopped the chain 72 is pulled downwardly, this acting to permit the spring 30 to move the thrust rod 20 in a direction to move the guard out of its operative position. The machine can 25 be started only after the chain 72 has been allowed to rise, this lowering the button clamp and bringing the guard into its operative position.

Having thus described certain embodi-

ments of this invention, it should be evident 35 to those skilled in the art that various changes and modifications might be made therein without departing from its spirit or scope as defined in the appended claims.

I claim:

1. In a button sewing machine, a button clamp, means for moving said clamp into and out of button-presenting position, sewing instrumentalities including a needle, a needle guard movable to and from guarding 45 position to protect the operator from flying pieces in case the needle breaks, and means actuated by said clamp moving means for moving said guard into and out of guarding position.

2. In a button sewing machine, a button clamp, means for moving said clamp into and out of button-presenting position, sewing instrumentalities including a needle, a needle guard movable to and from guarding 55 position to protect the operator from flying pieces in case the needle breaks, machine starting and stopping mechanism, means actuated by said clamp moving means for moving said guard into and out of guarding 60 position, and means actuated by said machine starting and stopping mechanism to retain said guard in guarding position while the machine is running.

In testimony whereof I have affixed my 65 signature.

ROBERT L. LYONS.
